GLOVE OR SIMILAR ARTICLE

Richard C. Zuckerwar, Gloversville, N.Y., assignor to Alexette Bacmo Corporation, Gloversville, N.Y.

Application August 15, 1958, Serial No. 52,225

Term of patent 7 years

(Cl. D3—11)

Fig. 1 is a rear view of a glove showing my new design; and

Fig. 2 is a front view thereof.

I claim:

The ornamental design for a glove or similar article, substantially as shown.
